(**) Term: **14 Years**

(57) **CLAIM**

(21) Appl. No.: **29/288,902**

The ornamental design for a plug for blood pressure measuring apparatus, as shown and described.

(22) Filed: **Jun. 26, 2007**

DESCRIPTION

(30) **Foreign Application Priority Data**

Apr. 23, 2007 (JP) 2007-10876

(51) **LOC (8) Cl.** **24-02**

FIG. 1 is a front, right side, top perspective view of a plug for

(52) **U.S. Cl.** **D24/169; D24/165**

blood pressure measuring apparatus showing my new design;

(58) **Field of Classification Search** D24/165–169,
